[57] CLAIM

The ornamental design for a retractable round card table top, as shown and described.

DESCRIPTION

FIG. 1 is a frontal perspective view of the retractable round card table top, the rear perspective view of the table top being a mirror image thereof;

FIG. 2 is a frontal perspective view of the table top of FIG. 1, with environmental structure shown in broken lines for purposes of illustration only and forming no part of the claimed design;

FIG. 3 is a top plan view of the table top of FIGS. 1 and 2 shown on a reduced scale;

FIG. 4 is a front elevational view of the table top of FIG. 3, the rear elevational view being a mirror image thereof;

FIG. 5 is a bottom plan view of the table top of FIG. 3;

FIG. 6 is a right side elevational view of the table top of FIG. 3, the left side elevational view being a mirror image thereof;

FIG. 7 is a frontal perspective view of an alternative embodiment, the only difference being that there are four retractable shelves;

FIG. 8 is a top plan view of the table top of FIG. 7 shown on a reduced scale;

FIG. 9 is a frontal perspective view of another alternative embodiment, the only difference being that there are five retractable shelves; and,

FIG. 10 is a top plan view of the table top of FIG. 9 shown on a reduced scale.
